CLAIM

The ornamental design for a subscriber identification module (SIM) card extraction tool carrier, as shown and described.

DESCRIPTION

FIG. 1 is a front view of a subscriber identification module (SIM) card extraction tool carrier;

FIG. 2 is a back view thereof;

FIG. 3 is a right side view thereof; the left side view is a mirror image of the right side view; and,

(Continued)

FIG. 4 is a top side view thereof; the bottom side view is a mirror image of the top side view.

The broken lines in FIGS. 1-4 show portions of the subscriber identification module (SIM) card extraction tool carrier that form no part of the claim.

1 Claim, 2 Drawing Sheets
